UNITED STATES PATENT OFFICE.

ROBERT C. MATHES, OF NEW YORK, N. Y., ASSIGNOR TO WESTERN ELECTRIC COMPANY, OF NEW YORK, N. Y., A CORPORATION OF NEW YORK.

VACUUM-TUBE CIRCUITS.

Original application filed October 23, 1916, Serial No. 127,120 $\frac{1}{2}$. Patent No. 1,426,754, dated August 22, 1922. Divided and this application filed October 17, 1919. Serial No. 331,466.

To all whom it may concern:

Be it known that I, ROBERT C. MATHES, a citizen of the United States, residing at New York, in the county of Bronx, State of New York, have invented certain new and useful Improvements in Vacuum-Tube Circuits, of which the following is a full, clear, concise, and exact description.

This invention relates to sources of direct current potential for the input circuit of a vacuum tube of the electron discharge type.

Its object is to provide a more convenient and desirable method than has heretofore been used for securing a desired difference of potential between the filament and the grip of a vacuum tube.

A further object is to furnish a means for securing desired differences of potential between the respective grids and filaments in circuits in which a plurality of electron discharge devices are employed.

In the embodiment of the invention shown herein a source of current separate from the sources of heating current and space currents is employed, and the input electrodes of the vacuum tubes are connected to suitable taps on an impedance adapted to be traversed by current from this separate source.

This application is a division of application Serial No. 127,120 $\frac{1}{2}$, filed October 23, 1916, patented August 22, 1922, No. 1,426,754.

These and other objects of the invention will be more fully understood from the following detailed description taken in connection with the accompanying drawing in which the view represents diagrammatically a circuit embodying the invention.

Referring to the drawing by reference numerals, the vacuum tube 1 contains the grid or control electrode 2, the filamentary cathode 3, and the anode 4. The vacuum tube 1' is similar and contains corresponding electrodes 2', 3' and 4'. Space current is supplied to the tubes by source 5. The cathodes 3 and 3' are connected in series with a source of heating current 6. The desired difference of potential between the grid and cathode of the respective tubes is obtained from a source of potential 7 which supplies current to the resistances 15, 9 and 9'. The drop in potential in resistance 9' is supplied

to the input circuit of tube 1', and the drop in potential in resistances 9 and 9' is supplied to the input circuit of tube 1. The values of these potential differences can be varied by changing the values of the respective resistances or of resistance 15.

The output circuit of tube 1 comprises inductance 11 in the direct current path, and condenser 12 and potentiometer resistance 26 in the alternating current portion of the circuit. The output circuit of tube 1' comprises inductance 11' and condenser 12', similar to the corresponding elements in the preceding circuit, and the primary of output transformer 13.

A choke coil 14 is placed in series with battery 6 to prevent fluctuations of the battery from affecting the operation of the tubes. For similar reasons series inductances 16 and shunt condenser 18 are placed in circuit with battery 7 and series inductance 21 and shunt condenser 20 in circuit with battery 5. In case sources 5 and 7 are storage batteries, they may be charged by connecting the generator 19 in circuit therewith.

Condensers 17 and 17' are placed in shunt to resistance 9 and 9' to provide an easy path for alternating currents. These condensers are particularly useful in minimizing cross-talk in case more than one amplifier of this type is operated from a common battery.

In operation signaling currents from the line 23 flow through resistances 24 and 25, these resistances being so proportioned that a desired amount of the potential drop there-through will be impressed on the input electrodes of tube 1. The amplified current from tube 1 is impressed through potentiometer 26 on the input electrodes of tube 1' and the reamplified current is transmitted through transformer 13 to a suitable line or other electrical device, not shown.

The arrangement whereby the output voltages of one tube are impressed on the input electrodes of another tube will be referred to in the claims as a tandem arrangement.

It will be noted that the batteries 7 and 5 are of the same type and will therefore be subjected to the same sort of fluctuations. If, for example, these batteries are dry cells, they will gradually drop in voltage as they are used, and a gradual drop in the voltage

of the output battery will be compensated for by a similar drop in the input battery. For example, if the anode becomes more positive the grid will become more negative and thus maintain the space current substantially constant. If these batteries are storage batteries, there will be a gradual drop in voltage of both input and output batteries during discharge. On closing the switch 19 for charging, there will be a sudden increase during the charging period. In any event any changes common to both batteries tend to compensate each other's effect.

15 While I have illustrated one form of the invention it is to be understood that the invention is not limited to the exact form shown but it entitled to equivalents within the scope of the appended claims.

20 What is claimed is:

1. In combination, a plurality of electron discharge devices each having an input terminal, a source of potential, a plurality of taps of different potentials at points in series on said source, and a connection from each of said input terminals to one of said taps.

30 2. In combination, a plurality of electron discharge devices each having an input terminal, said devices being arranged in tandem, a source of potential, a plurality of taps of different potentials at points in series on said source, and a connection from each of said input terminals to one of said taps.

35 3. In combination, a plurality of electron discharge devices, each having an input terminal, a source of current, an impedance in circuit with said source, a plurality of taps at points in series on said impedance, and 40 connections from said taps to said input terminals.

45 4. In combination, a plurality of electron discharge devices each having a cathode and a control electrode, a source of current, an impedance adapted to be traversed by current from said source, and connections from points in series on said impedance to said cathodes and control electrodes.

50 5. In combination, a plurality of electron discharge devices each having a cathode and a control electrode, a source of current, an impedance adapted to be traversed by current from said source, said cathodes being connected to the more positive end of said impedance, and said control electrodes being connected to points in series on said impedance.

60 6. In combination, an electron discharge device having a control electrode, a cathode, and a cathode heating circuit, a source of current, and an impedance in circuit with said source, said heating circuit being connected to one end of said impedance, and said control electrode being connected to a point intermediate the ends of said im-

pedance, said control electrode being thereby normally maintained at a potential different from that of any part of said cathode.

7. In combination, an electron discharge device having a control electrode and a filamentary cathode, a source of current, an impedance adapted to be traversed by current from said source, connections from both ends of said cathode to the more positive end of said impedance and a connection 70 from said control electrode to a point intermediate the ends of said impedance, said control electrode being thereby maintained more negative than any part of said cathode.

8. In combination, a plurality of electron 80 discharge devices, each having an input terminal, a source of current, an impedance in circuit with said source, a plurality of taps on said impedance, a condenser connected between each two adjacent taps, and 85 a connection from each of said input terminals to a tap on said impedance.

9. In combination, a plurality of electron discharge devices each having a cathode and a control electrode, a source of potential, a 90 plurality of taps of different potential at points in series on said source, a connection from each of said control electrodes to one of said taps, said cathodes being connected to one end of said source, each of said control electrodes being thereby normally maintained at a potential different from any part of the corresponding cathode.

95 10. In combination, a plurality of electron discharge devices each having a cathode and a control electrode, a source of potential, a plurality of taps of different potential at points in series on said source, a connection 100 from each of said control electrodes to one of said taps, said cathodes being connected to the positive end of said source, each of said control electrodes being thereby normally maintained more negative than any part of the corresponding cathode.

110 11. In combination, a plurality of electron discharge devices each having a cathode and a control electrode, means for passing heating current serially through said cathode, a source of potential, a plurality of taps of different potential at points in series on said source, a connection from each of said control electrodes to one of said taps, said cathodes being connected to the positive end of said source, each of said control electrodes being thereby normally maintained more negative than any part of the corresponding cathode.

115 12. In combination, a plurality of electron discharge devices each having a cathode and a control electrode, a source of current, an impedance adapted to be traversed by current from said source, said cathodes being connected to the more positive end of said impedance, and said control electrodes being 120 connected to points in series on said 130

impedance, and capacities providing paths of low impedance to alternating current, connecting said points to said end of said impedance.

- 5 13. In combination, a plurality of electron discharge devices each having a cathode and control electrode, a source of current, an impedance adapted to be traversed by current from said source, connections from points in series on said impedance to said cathodes and control electrodes, and capacities providing paths of low impedance to alternating current, connected across said connections.
- 10

14. In combination, a plurality of electron discharge devices each having an input terminal, a source of potential, a plurality of taps of different potentials at points in series on said source, a connection from each of said input terminals to one of said taps, and capacities providing paths of low impedance to alternating current, connected between said taps. 15

In witness whereof, I hereunto subscribe my name this 14th day of October, A. D. 25 1919. 20

ROBERT C. MATHES.
